UNITED STATES PATENT OFFICE.

EDWIN F. BEUGLER, OF BUFFALO, NEW YORK, ASSIGNOR TO EDWARD B. HOLMES, OF BUFFALO, NEW YORK.

MACHINE FOR DRIVING HOOPS ONTO KEGS.

No. 923,759.

Specification of Letters Patent.

Patented June 1, 1909.

Application filed April 11, 1906. Serial No. 311,061.

To all whom it may concern:

Be it known that I, EDWIN F. BEUGLER, a citizen of the United States, residing at Buffalo, in the county of Erie and State of New York, have invented a certain new and useful Improvement in Machines for Driving Hoops onto Kegs, of which the following is a specification.

This invention relates to an improved machine for driving hoops upon kegs, such as nail kegs or the like, in which the hoops are driven simultaneously upon both ends of the keg or the like.

One feature of the invention has reference 15 to a novel hoop driving mechanism in which the driving arms are automatically closed around the keg as the hoop driving mechanism is operated to drive the hoops into place, and automatically opened as the hoop driving mechanism recedes from the keg after the hoops have been driven home.

Another feature of the invention has reference to a novel driving mechanism, so that both driving heads are given a simultaneous forward and back movement toward and from the keg.

The object of the invention is to produce a machine of simple, cheap and light construction, occupying a minimum of space and 30 adapted to operate at a comparatively high rate of speed.

The invention also relates to certain details of construction all of which will be fully and clearly hereinafter described and 35 claimed, reference being had to the accompanying drawings, in which,—

Figure 1, is a front elevation of the improved machine. Fig. 2, is an end elevation of the improved machine looking in the direction of the arrow V, Fig. 1. Fig. 3, is a transverse section through the machine on line a—a, Fig. 1, the keg support being omitted. Fig. 4, is a longitudinal section through the machine on line b—b, Fig. 2, the eccentric mechanism being shown in elevation. Fig. 5, is a horizontal section through the machine on line c—c, Fig. 1. Fig. 6, is an enlarged transverse section through the cone levers and their connecting springs on line d—d, Fig. 4. Fig. 7, is an enlarged fragmentary end view of the machine frame, showing a section through the driving mechanism. Fig. 8, is an enlarged central longitudinal section on line e—e, Fig. 4, through one of the levers for operat-

ing the hoop driving mechanism. Fig. 9, is an enlarged view of one of the cone levers showing the cone in dotted lines. Fig. 10, is an enlarged fragmentary section through one of the adjustable barrel supports on line f—f, Fig. 1. Fig. 11, is an enlarged detached fore view of one of the ribbed plates of the adjustable barrel supports. Fig. 12, is an enlarged section through a part of the machine frame and the movable fulcrum of one of the levers for operating the driving heads. Fig. 13, is an enlarged detached outer end view of one set of hoop driving mechanism. Fig. 14, is an enlarged detached inner end view of one set of hoop driving mechanism. Fig. 15, is an enlarged detached view of one of the driving arms. Figs. 16 and 17, are opposite face views of one of the hoop driving plates. Fig. 18, is a section on line g—g, Fig. 13, two of the driving arms being shown in their normal or open position and the remaining arms being omitted. Fig. 19, is a view similar to Fig. 18, showing the two driving arms partially closed. Fig. 20, is an enlarged section through one of the driving arms on line h—h, Fig. 15. Fig. 21, is an enlarged section on line i—i, Fig. 1. Fig. 22, is a detached plan view of the arm for retaining the starting lever in its position.

In referring to the drawings for the details of construction, like numerals designate like parts.

The machine frame.—The frame of the machine consists of two vertical end members 1 and 2, which are connected by longitudinal side members 3. The lower portion of each end member consists of two vertical legs connected near their lower ends by a transverse cross piece or brace 4; and the upper portion of each end member is substantially A shaped, see Fig. 2. The ends of the side members 3, are secured by bolts to the vertical end members 1 and 2, at about the point where the vertical legs merge into the A shaped portion, see Fig. 3. A horizontal opening is formed in the apex of each vertical end member and a longitudinal tie rod 5, has its ends screw threaded and passed through said openings, the rod being secured in place by nuts screwed upon its ends as shown in Figs. 1, 2, 3 and 4. Each of the cross pieces or braces 4, has a central vertical lug 6, provided with a horizontal opening through which the screw threaded ends of a

85

90

95

100

105

110

lower tie rod 7, are passed. The rod 7, is secured in place by nuts screwed thereon and against the opposite sides of the lugs, see Figs. 4 and 12. By this construction it will 5 be seen that a frame is produced which is simple, light, and composed of few parts, is extremely rigid and occupies but a minimum of space.

The driving mechanism.—The driving 10 mechanism for operating the hoop driving mechanisms is illustrated in Figs. 1, 2, 4, 5 and 7, to which figures reference will be had in the following description. A transverse driving shaft 8, is journaled in bearings 9, 15 formed on the inner side of the legs of the end frame member 1, and said driving shaft has a pinion 10, which meshes with a spur gear wheel 11, on a counter-shaft 12. This countershaft is journaled in bearings 13, 20 formed in brackets 14, which are secured by bolts 15, to the outside of the leg portions of the end frame member 1. The spur gear 11, has a pinion 16, formed integral therewith, and said pinion meshes with a spur gear 17, 25 mounted on a main shaft 18, which is journaled in bearings 19, formed in the brackets 14, and almost vertically above the bearings 13. The driving shaft 8, is rotated by a pulley 20, loosely mounted upon a projecting 30 portion of the shaft, the pulley being held against lateral movement in one direction by a collar 21, secured to the shaft by a set screw, see Fig. 7. The pulley is locked to the shaft to rotate the same, by a clutch 35 mechanism which is fully shown in Fig. 7. A sliding sleeve 22, is mounted upon the end of the shaft so as to have a longitudinal movement on said shaft, but is prevented from independent rotation by two keys or 40 feathers which work in longitudinal keyways in the shaft, see Figs. 1 and 7. At the end of the sleeve nearest the pulley 20, are two oppositely extending lugs 23, in each of which is seated a pin 24. These pins project 45 laterally from the faces of the lugs and are adapted to engage with two similar pins 25, which project laterally from the hub of the pulley 20, and so lock the pulley temporarily to the sleeve. The outer end of the sleeve 22, 50 is reduced and a ring 26, is loosely fitted upon said reduced portion and held in place by a collar 27. The ring has two oppositely extending pins, 28, adapted to seat in the forked ends of a yoke lever 29, which is securely fastened at its lower end to a longitudinal rock shaft 30. The rock shaft is 55 preferably square in cross-section with the exception of its ends which are round. These ends are seated in vertical depressions in the outer ends of two bracket-like arms 31, extending from the foot of one of the legs of each end frame member, which form bearings for said shaft, see Figs. 1 and 7. The shaft is rocked to move the clutch sleeve into 60 or out of engagement with the pulley, by 65

means of a hand lever 32, which is fastened at its lower end to the rock shaft and extends in a substantially vertical direction to within convenient reach of the operator, see Figs. 1 and 7. The lever is moved in a direction toward or from the machine to rock the shaft and thus start or stop the machine, and is automatically locked in either position by a simple and efficient device illustrated in Figs. 1, 5, 7 and 22.

By referring to Figs. 3 and 21, it will be noticed that the longitudinal side frame members 3, are of channel bar cross section. A horizontal bar 33, has its inner end in the form of a hook, which hooks over the inner edge of the lower horizontal portion of the frame member, and its outer end provided with a curved slot 34. This bar is located so that its outer end is in close proximity to the starting and stopping lever 32, and a bolt 35, is passed loosely through an opening in said lever and through the curved slot 34. A vertical pocket is formed in the bar near its rear end and a coiled compression spring 36, is seated in said pocket and exerts a pressure against the bottom surface of the side frame member, thus tending to depress the outer end of the bar, see Fig. 21.

It will be seen that owing to the slope of the slot 34, the bolt 35, will be retained in either end thereof, by the downward tendency of the outer end of the bar and thus prevent the jar of the machine from involuntarily releasing the hand lever and operating the clutch. When the operator shifts the hand lever 32, the bolt riding in the slot, raises the end of bar against the tension of the spring 36, until said lever is past the center, when the bolt slips into its seat in the end of the slot.

The eccentric mechanism for operating the hoop driving mechanism.—As before stated, the hoop driving mechanisms are given a forward and back or reciprocating movement toward and from the keg. This is driven by means of a pair of eccentrics connected to a pair of levers supported at one end by movable fulcrums, and connected at their other ends to the hoop driving mechanisms. This mechanism is illustrated in Figs. 1, 2, 3, 4, 5, 6, 7, 8 and 12.

There are two separate sets of hoop driving mechanisms each of which drives the hoops upon one end of the keg. These hoop driving mechanisms are duplicates, each consisting of a driving head; a centering and shaping cone for accurately centering the keg and spreading the ends of the staves; and a plurality of driving arms having a radial movement.

The two sets of hoop driving mechanisms are slidably supported upon two horizontal extending bars 37 and 38, which are supported by having their outer ends rigidly clamped in openings formed in transverse

braces 39, in the A shaped portions of the end frame member 1 and 2. These braces are split and are drawn against the bars by clamping bolts as shown in Fig. 2.

5 The driving mechanisms are given a reciprocating movement on the bars 37 and 38 by a pair of eccentrics 40 and 41, mounted upon the main shaft 18. These eccentrics work oppositely to each other and have eccentric 10 straps 42 and 43, which are connected by eccentric rods 44 and 45, to two levers 46 and 47 supported at their lower ends by movable fulcrum blocks 48 and 49. The levers 46 and 47, are each preferably constructed of two parallel bars having openings in their lower ends in which oppositely extending pins 50, projecting laterally from the fulcrum blocks fit. The parallel bars composing each lever extend upwardly and 15 are separated from each other, the upper ends thereof straddling the hubs 51 and 52, of the driving heads 53 and 54. As shown in Figs. 1, 4 and 8, portions of the sides of the hubs are cut away to form depressions in 20 which the upper ends of the levers seat. The end walls of the depressions are shaped so as to provide a working point for the levers and so reduce friction.

25 A bolt 55, ties the upper ends of the bars composing the levers, and a roller 56, is supported by this bolt and rolls on the top surface of the hubs 51 and 52, see Fig. 8.

The ends of the eccentric rods 44 and 45, are secured to an intermediate point of the 30 levers by fitting their ends between the bars comprising said levers, and securing them in place by bolts 57, see Figs. 3 and 8.

The fulcrum blocks 48 and 49, are supported by bars 58 and 59, and have a slight 35 longitudinal movement against the tension of springs. These bars 58 and 59, have their outer ends passed through openings in the cross pieces or braces 4 and their inner ends passed through openings in the fulcrum 40 blocks. The blocks are adjustable on the bars and are locked in place by locknuts 60, screwed against both sides of the blocks, see Fig. 12. Heavy coiled depression springs 61, encircle the center projecting ends of the bar 45 58 and 59, said springs being held in place by spring capes 62, and screw nuts 63. Lock nuts 64, on the bars, screwed against the inner sides of the cross pieces or braces 4, prevent the outward movement of said bars, see 50 Fig. 12. The fulcrum blocks are guided in a longitudinal direction and prevented from lateral movement by vertically extending forked projections 65, projecting from the top surface of the blocks and straddling the 55 lower tie rod 7.

By referring to Fig. 7, it will be seen that the eccentrics 40 and 41, are cast in one integral piece of metal. This method is preferred as it obviates the possibility of one of 60 the eccentrics slipping on the shaft and so

changing its position with respect to the other eccentric. Besides being secured to the shaft by a key, the eccentrics are rigidly fastened to the spur gear 17, by bolts 66, so that the real driving strain is borne by said 70 spur gear instead of the shaft.

The hoop driving mechanism.—As before stated there are two sets of hoop driving mechanisms and as these sets are exact duplicates, but one set will be described, like 75 parts on both sets being designated by like numerals except where it is thought necessary to distinguish between like parts on both sets to more clearly set forth the construction or operation.

In the following description, reference will be particularly had to Figs. 1, 3, 4, and 13 to 20 inclusive of the drawings to which attention will be frequently called.

The driving heads 53 and 54 are preferably formed as shown in Figs. 13 and 18 being circular in form and having central hubs 51 and 52. Each driving head has a plurality of radially extending Y shaped arms 67, which radiate from the central hub, 80 and terminate at their outer ends in lugs 68, between which the driving arms are pivoted. A cross piece 69, connects the branches of each Y shaped arm to the branches of the adjacent Y shaped arm, said cross piece being located near the outer termination of the arms, and thus forms pockets 70, the purpose of which will be described farther on.

The centering and shaping cone is in the form of an annular ring having a cone 100 shaped or beveled portion 71, a cylindrical portion 72, and an annular flange 73. This ring is connected to a central hub 74, by radial arms 75, said hub being loosely supported upon one of the bars 37 and 38, adjacent to the driving head, see Figs. 14 and 15. A plurality of equally spaced, diagonally extending radial arms 76, extend outwardly from the annular flange 73, the outer extremities of the arms being bent forward at 105 about right angles to form hook portions as shown in Fig. 19. The radial arms 76, extend in a diagonal direction toward the adjacent driving head at about an angle of forty-five degrees and are grouped in pairs, 110 the members of each pair extending parallel to each other, and the pairs being equal in number to the number of driving arms.

In the preferred form of hoop driving mechanism as illustrated in the accompanying drawings, each driving head has eight driving arms 77, the outer end of each driving arm being pivoted between a pair of the lugs 68, by a pin. These driving arms extend horizontally toward the centering cone, 115 and have their inner ends passing between two of the parallel radial arms 76, said inner ends being supported by rollers 78, mounted on pins extending transversely through the driving arms as shown in Figs. 15 and 18. 120 125 130

These rollers work on the diagonal surface of the arms 76, which are flat and smooth.

The inner ends of driving arms are drawn toward the center as the driving head moves 5 toward the cone, by springs 79, encircling bolts 80, seated in the pockets 70, and having their outer ends passed through openings in the cross pieces 69, and in the driving arms, and are spread as the driving head moves 10 away from the cone, by the rollers working upon the diagonal surfaces of the radial arms 76. Nuts are screwed upon the outer ends of the bolts 80, by means of which the tension of the springs 79, may be regulated.

15 A driving plate 81 is affixed to the inner end of each driving arm by a bolt 82, so as to have a slight rocking motion on said bolt in order to adapt itself to the shape of the keg upon which hoops are being driven. 20 The bolt 82, is locked against involuntary withdrawal by a longitudinal pin 83, seated in a depression in the arm and having a chisel edge which is adapted to be embedded in the end of the bolt. The pin 83, is moved 25 to embed its point in the bolt by a set screw 84, having a cone point which engages with the beveled opposite end of the pin, see Fig. 20. Each driving plate is formed so as to have four driving edges, so that when one 30 edge is worn, the plate can be given a quarter turn to bring a screw edge into use.

While the plates have a slight rocking motion, they are held against involuntary rotation on the bolt 82, by pins 85, seated in the 35 ends of the driving arms and having their outer ends seated in depressions 86, in the adjacent faces of the plates. The pins are forced outwardly by coiled springs, 87, see Fig. 20. Small openings 88, lead from the 40 depressions 86 to the outer surface of each plate, through which openings an instrument is introduced to push back the pin 85, against the tension of the spring when it is desired to turn the plate to bring a new 45 driving edge into use.

The centering and shaping cones are forced into the open ends of the keg by a pair of forked levers 89, which are connected by a pair of coiled extension springs 90, see 50 Figs. 1, 4, 5, 6 and 9. These levers 89, are pivoted by bolts at their lower ends to fulcrum blocks 91, secured by set screws to the lower tie rod 7, and about vertically below the centering cones when said cones are in 55 their normal positions as shown in Figs. 1 and 4. The upper ends of the levers are forked, as shown at 92, and straddle the hubs 74, of the cones, the edges of the forks seating against lugs 93, on the cones, see Figs. 1 and 9. A clip 94, having a forked portion and two laterally extending portions, straddles each lever 89, at a point about midway of its length, and a U shaped bar 95, has its ends screw threaded and passed through 65 openings in the lateral portions of the clip

being held in place by nuts. The coiled extension springs 90 have their ends connected to the inner ends of the U shaped bars 95, and tend to draw the levers 89 toward each other.

70 While the centering and shaping cones have a limited longitudinal movement on the bars 38 and 39, they are held against rotation on or displacement from said bars by longitudinal rods 96, having their inner ends 75 passed through slots in the driving heads and provided with eyes which hook over a vertical pin 97, in the hubs of the centering cones see Figs. 1 and 4. The outer ends of the rods 96, pass through openings in the A shaped portion of the end frame member, and have collars 97, fastened thereon by set screws. The inward movement of the centering cones can be regulated by moving the collars to different points on the rods, the 80 movement of the cones being stopped when the collars strike against the end frame members.

An adjustable support for the keg is provided, said support consisting of a pair of 90 channel bars 98, which extend transversely across the center of the machine and are supported by adjustable brackets 99, bolted to the side frame members 3, see Fig. 5. A ribbed plate 100, having a horizontal 95 rib on its inner surface and a vertical rib on its outer surface, is interposed between each of the brackets 99, and the side frame member; the horizontal rib fitting in a horizontal slot in the side frame members and the vertical rib fitting in a vertical slot in the brackets 99, the brackets and the plates being securely fastened to the frame members by bolts 101, see Figs. 1 and 10. By 100 this means both a vertical and a horizontal adjustment of the barrel support is provided.

105 Horizontally extending angle irons 102, are secured by screws to the upper portions of the brackets 99, so that they extend from the front and rear sides of the machine. When operating the machine, the operator places a keg upon the angle irons and rolls it into the place upon the bars 98, see Figs. 1 and 4.

110 The operation of the machine is as follows:—The various parts of the machine being in the position shown in Figs. 1 and 4, the operator places the end and bilge hoops upon a keg and places said keg in position 115 as above described. Then grasping the handle at the end of the lever 32, he moves it toward the machine, thereby rocking the shaft 30, and throwing in the clutch. This locks the pulley 20 to the driving shaft 8, and causes said shaft to revolve, which motion is transferred to the main shaft 18, by the pinion 10, spur gear 11, pinion 16 and spur gear 17. As the gear 17 and shaft 18 120 revolve, the eccentrics 40 and 41, rock the 125 gear 17, which causes the driving plates 81 to 130 revolve, and the keg is shaped.

levers 46 and 47 on their pivots and draw their upper ends toward each other and move the driving heads toward the keg. When this movement begins the coiled 5 springs 90, impart a similar movement to the levers 89, and draw their upper ends toward each other thereby moving the centering cones toward the keg. As the cones enter the open ends of the keg, the ends of 10 the staves are spread by the cone surfaces 71, until the ends of the keg are perfectly circular in form, the movement of the cones being stopped by the annular flanges 73, which drive the end hoops into place. It 15 will be noticed that while the foregoing operation is being performed, the position of the cones relatively to the driving heads does not change, the cones and driving heads moving at equal speed. The cones are now 20 firmly seated in the ends of the keg which is accurately centered between the driving heads. The continued movement of the driving hubs carries the driving arms 77, toward the keg, the inner ends of said arms 25 closing around the barrel as the rollers 78, roll down the inclined surface of the radial arms 76, until the driving edges of the driving plates contact with the staves when the continued inward movement of the driving 30 heads drives home the bilge hoops.

By referring to Figs. 1, 4, 18 and 19, it will be seen that a series of collars 103, loosely encircle the bars 37 and 38, between the driving heads and the hubs of the centering cones. As the driving heads move 35 toward the keg, they come into contact with these collars and exert an increased pressure on the cones, thereby driving the end hoops into place by means of the annular flanges 40 73. By increasing or lessening the number of collars, the pressure against the cones may be increased or reduced. The driving heads have now reached the limit of their inward movement and the hoops have been 45 driven into place. The eccentrics now complete the remaining half of their revolution and the return stroke of the eccentric rods return the driving heads to their normal position. At the instant that the driving heads 50 commence this return movement, the inner ends of the driving arms open or move away from the sides of the keg. This movement is caused by the rollers 78, rolling up the inclined surface of the radial arms 76, as the driving heads recede until said rollers seat 55 in the outer hook ends of said arm. The arms 77, open against the tension of the spring 79, but the tension of the springs 90 is sufficient to overcome this tension and the 60 cones remain in their position until the driving arms reach the limit of the outward movement when the cones are drawn back with the driving heads.

The object in providing movable fulcrums for the levers 46 and 47, is to allow

for the inequalities in the sizes of kegs, caused by unequal shrinkage of the staves and also for inequalities in the sizes of the hoops. It is obvious that by using eccentrics to operate the levers a certain definite 70 length of stroke will be had at each revolution of the main shaft 18. The object in this class of work is not to drive the hoops a certain distance upon the keg, but to drive them into place with a certain pressure. In 75 this machine, this object is obtained by using fulcrums for the levers 46 and 47, which are movable against the tension of springs.

By referring to Fig. 4, it will be seen that when driving the hoops into place the hoops 80 are driven until the driving pressure becomes greater than the tension of the springs 61, when said springs will give and the lower ends of the levers 46 and 47, with their fulcrums will move instead of their upper ends 85 while the remaining portion of the stroke is completed.

It is obvious that by adjusting the nuts 63, and thus regulating the tension of the springs 61, the hoops can be driven upon the 90 keg with a predetermined pressure.

I claim as my invention.

1. In a machine of the class described, a machine frame, two opposed hoop driving mechanisms, a support for a keg or the like 95 between said hoop driving mechanisms and means for simultaneously moving said hoop driving mechanisms toward or from each other consisting of a pair of levers connecting at their upper ends to the hoop driving 100 mechanisms, fulcrums supporting the lower ends of the levers, spring mechanism for yieldingly tensioning the fulcrums and a pair of eccentrics connected to intermediate portions of the levers. 105

2. In a machine of the class described, a machine frame, two opposed hoop driving mechanisms, a support for a keg or the like between said hoop driving mechanisms, and 110 means for simultaneously moving said hoop driving mechanisms horizontally toward or from each other consisting of a pair of approximately vertical levers each of which is connected at its upper end to one of the hoop driving mechanisms, two eccentrics, one of 115 which is connected to an intermediate portion of each lever, two movable fulcrums each of which supports the lower end of one of the levers and spring mechanism for yieldingly tensioning the fulcrums. 120

3. In a machine of the class described, a machine frame, two opposed hoop driving mechanisms, a support for a keg or the like between said hoop driving mechanisms, and means for simultaneously moving said hoop 125 driving mechanisms horizontally toward or from each other consisting of a pair of approximately vertical levers each of which is connected at its upper end to one of the hoop driving mechanisms, two eccentrics, each of 130

which is connected to an intermediate portion of one of the levers, mechanism for moving said eccentrics oppositely to each other, and two movable spring tensioned fulcrums each of which supports the lower end of one of the levers.

4. In a machine of the class described, a machine frame, two opposed hoop driving mechanisms, each having driving arms, a support for a keg or the like between said hoop driving mechanisms, means for moving said hoop driving mechanisms relatively to each other, and means for automatically closing the driving arms around the keg or like article as the hoop driving mechanisms are moved to drive the hoops and automatically opening the driving arms as the hoop driving mechanisms recede; said means consisting of a series of radial arms having inclined surfaces and rollers supported from the driving arms and engaging the inclined surfaces of the radial arms.

5. In a machine of the class described, a machine frame, two opposed hoop driving mechanisms, a driving shaft, a support for a keg or the like between said hoop driving mechanisms, means for simultaneously moving said hoop driving mechanisms toward or from each other including eccentrics operated from the driving shaft, levers operatively connected near their middle to the eccentrics and at their upper ends to the hoop driving mechanisms and movable spring tensioned fulcrums connected to the lower ends of the levers.

6. In a machine of the class described, a machine frame, two opposed hoop driving mechanisms, a support for a keg or the like between said hoop driving mechanisms, a driving shaft, approximately vertical levers connecting at their upper ends to the hoop driving mechanisms, spring tensioned fulcrum blocks supported from the frame and attached to the lower ends of the levers and eccentrics operated from the driving shaft and engaging an intermediate portion of the levers.

7. In a machine of the class described, a machine frame, two opposed hoop driving

mechanisms, a support for a keg or the like between said hoop driving mechanisms, a shaft, two oppositely arranged eccentrics on said shaft, a bar extending from each eccentric and two levers each connected to one of the bars and one of the hoop driving mechanisms; said levers comprising two parallel bars separated from each other and having their upper ends straddling the hubs of the hoop driving mechanisms, and their lower ends connected to fulcrum rods yieldingly supported from the frame.

8. In a machine of the class described, a machine frame, two opposed hoop driving mechanisms, a support for a keg or the like between said hoop driving mechanisms, a driving shaft and operating levers actuated from the driving shaft and connecting to the hoop driving mechanisms; said levers being yieldingly spring fulcrumed from the machine frame.

9. In a machine of the class described, a machine frame, two opposed hoop driving mechanisms, a support for a keg or the like between said hoop driving mechanisms, a driving shaft and eccentric mechanism operated from the driving shaft and including levers connecting at their upper ends to the hoop driving mechanisms and yieldingly fulcrumed at their lower ends from the machine frame.

10. In a machine of the class described, a machine frame, two horizontally movable opposed hoop driving mechanisms adapted to reciprocate toward and from each other, a driving shaft, levers having their upper ends connected to the hoop driving mechanisms and means operated from the driving shaft and connected to the levers for moving said levers to shift the hoop driving mechanism and spring fulcrums attached to the lever whereby the hoop driving mechanisms are yieldingly balanced against the tension of the springs when the driving pressure becomes sufficiently great.

EDWIN F. BEUGLER.
